UNITED STATES PATENT OFFICE.

FREDERICK W. BELKO, OF MODEL CITY, NEW YORK.

DESIGN FOR A FRAME FOR FRUIT-PARERS.

SPECIFICATION forming part of Design No. 35,559, dated January 7, 1902.

Application filed November 25, 1901. Serial No. 83,656. Term of patent 14 years.

To all whom it may concern:

Be it known that I, FREDERICK W. BELKO, a citizen of the United States, residing at Model City, in the county of Niagara and State of New York, have invented and produced a new and original Design for the Frame of a Fruit-Parer, of which the following is a specification, reference being had to the accompanying drawings, forming a part thereof.

This design relates to the configuration of the frame of a fruit-parer.

The accompanying drawing is a perspective view of a frame embodying my new design.

As shown in the drawing, the leading feature of the design consists of posts or standards A A', a horizontal bar B, connecting the upper ends of the standards, an overhanging bracket C, extending forwardly from one end of said connecting-bar and arranged at right angles thereto, and a yoke D, arranged at the free end of said bracket.

The standards A A' have perforated base-flanges a and vertical webs a', located at the

junction of said flanges and the standards. A cross-bar E connects the lower ends of the standards A A', and extending upwardly from the middle of this cross-bar to the upper connecting-bar B is an intermediate standard F. G indicates a brace extending forwardly from the upper connecting-bar B to a point near the front end of the bracket C. On this brace is a perforated boss g, and opposite the latter in the bracket C is an opening g'. The opposite end of the upper connecting-bar B has an opening h and terminates in a bill-like extension h'.

I I' indicate opposing openings in the outer end of the bracket C and the terminal member d of the yoke D.

What I claim is—

The design for the frame of a fruit-parer, substantially as herein shown and described.

Witness my hand this 16th day of November, 1901.

FREDERICK W. BELKO.
